UNITED STATES PATENT OFFICE

ALEXANDER SCHMITZ, OF HEERDT, NEAR DUSSELDORF, GERMANY.

PROCESS OF MAKING FATTY COMPOUNDS FOR USE AS TURKEY-RED OILS.

964,565.

Specification of Letters Patent. Patented July 19, 1910.

No Drawing.

Application filed July 31, 1907. Serial No. 386,391. (Specimens.)

To all whom it may concern:

Be it known that I, ALEXANDER SCHMITZ, doctor of philosophy, of Heerdt, Germany, a subject of the King of Prussia, and whose 5 post-office address is Heerdt, near Dusseldorf, Prussia, German Empire, have invented a new and useful Process of Manufacturing Fatty Compounds for Use as Turkey-Red Oils; and I do hereby declare 10 that the following is a full, clear, and exact description of my invention, which will enable others skilled in the art to which it app pertains to make and use the same.

The present invention has for its object 15 the hereinafter described improvement upon the process of manufacturing fatty compounds for use as Turkey red oils described in Patent No. 861,397 granted July 30, 1907.

According to the above prior process a 20 mixture of fatty oxy-acid compound and castor oil or other fatty oils or fats has to be heated up to 40-100° C. and cooled back to the room temperature before it is subjected to the sulfonation step. Now I have dis- 25 covered that a perfect sulfonation of the said mixture can be obtained without previously heating and subsequently recooling the mixture. This discovery is of great practical importance for the reason that, as any 30 expert will at once admit, the heating of the fatty mixture is a troublesome operation requiring careful watching by an experienced man; moreover, the consumption of fuel and the heating appliances needed involve corre- 35 sponding expenses whereby the product is rendered more costly. It is by the application of my said new discovery that I have succeeded in getting rid of these inconveniences without doing harm to the specific 40 peculiarities of the product nor reducing the yield of the process.

In carrying out the improved process I proceed as follows: I take fatty oxyacid compounds obtained from fatty substances 45 having the character of castor oil, that is to say castor oil itself, similar fatty oils, and fats of the vegetable and animal kingdoms or mixtures of castor oil, or similar fatty oils and fats with other fatty oils, fats or 50 fatty acids, such as oleic acid, olein, ricinoleic acid and the like.

The substances used of the character of castor oil are intended to be the known substitutes for castor oil, in so far as the manu- 55 facture of Turkey red oils and their substitutes is concerned. Such substances are for

instance the following:—1. olive oil, almond oil, arachis oil, rape oil, sesamē oil, cotton-seed oil, and the like non-drying oils; 2. sunflower oil, linseed oil, hemp oil and the like 60 drying oils; 3. cocoanut oil, palm oil, beef tallow, mutton fat and the like solid oils and fats; 4. free fatty acids such as oleic acid, linoleic acid, the fatty acid of cotton-seed oil and the like. These fatty 65 oxyacid compounds are produced in the usual manner which is as follows: Castor oil or its desired substitute is sulfonated by means of sulfuric acid in the manner usual in the manufacture of Turkey red oil. The 70 sulfonation being completed, the product of the reaction is freed from adherent sulfuric acid by washing with pure water or alkaline water, then separated from the under lye and continuously boiled either alone or with 75 water in an open vessel until the sulfoacid compound formed in the sulfonating step is split up and the sulfuric acid completely disengaged from the oil. By this means the oil is rendered completely insoluble in water 80 and, as is known, is transformed into the corresponding fatty oxy-acid compound.

The fatty oxy-acid compound being washed thoroughly free from sulfuric acid and dehydrated, is mixed in the mixing vat 85 with castor oil or other similarly acting fatty oils or fats at ordinary temperature. The mixture as it is, that is to say without being previously heated and cooled back to the room temperature, is sulfonated by 90 means of sulfuric acid in the manner usual in the manufacture of Turkey-red oil, and allowed to stand until a sample of the sulfonation product mixed with some alkali 95 dissolves in hot lime water without separating out insoluble lime-soap, forming a limpid liquor. When this is obtained, the mixture resulting from the reaction is well washed with pure water or an alkaline water, and allowed to stand for one or two 100 days, when the oily product, that has collected on the surface is drawn off from the under lye and finally mixed with alkali so proportioned as to produce an acid or a neutral or a basic oil according to requirements. If desired, the oily product drawn off from the under lye may be transformed 105 into soap by boiling it with an alkali.

The process is not limited to any strict mixing proportions between the fatty oxy-acid compounds and oil or fat, as such proportions may vary within wide limits 110

(25-75 per cent. of fatty oxy-acid compound to 75-25 per cent. of oil or fat).

The second sulfonation has the effect of sulfonating both the oxy acid and the oil 5 not sulfonated mixed therewith. The object is to manufacture an oil which shall be soluble in water at the same time presenting hydroxyl groups (HO) for reaction with the alumina or other metallic 10 oxid present in the mordant. The oxy-acid is that component to which the hydroxyl groups are bound. However, this oxy-acid is insoluble in water and therefore it must be sulfonated as well as the oil to be combined therewith which is likewise insoluble 15 in water in the unsulfonated state. The proportion of oxy-acid depends upon the degree of reactivity or the amount of hydroxyl groups desired by the user of the oil to be 20 present in the latter. The hydroxyl groups are split off by the action of the metal salt present in the mordant and replaced by the oxid of said salt, for instance, alumina. The more hydroxyl groups which are replaced 25 by alumina, the more color will be deposited upon the fiber, and vice versa. Therefore if deep shades are to be produced, an oil must be used that is correspondingly rich in hydroxyl groups, whereas an oil 30 less rich in said groups must be used when lighter shades are to be produced. On the other hand there are dyers who like to use thinned oils (diluted with much water), whereas others like to operate with concentrated oils. Now, in order to obtain the 35 same effect the oils for preparing the thin solution required in the first case must be provided with more hydroxyl group, that is to say, must have a greater proportion of 40 oxy acid than the oil employed for preparing the concentrated solution of oil in water. Thus each individual dyer desires to have in the oil that percentage of oxy acid which he considers most suited for his 45 purpose and such percentage as he desires is used by the applicant in manufacturing the oil. The percentage of alkali is varied according to the request of the user to be furnished with an acid soap, or a neutral 50 soap or a basic soap.

Acid oils are used in the operations of dyeing and printing with alizarin colors (Turkey red). For this purpose so much alkali is added to, or incorporated into, the 55 oil obtained by the second sulfonation, that it shows a weak acid reaction when tested with litmus-paper. The special degree of acidity desired by the user is then produced by the user himself by further addition of 60 alkali.

Neutral oils are principally used in the operations of "finishing (dressing)" and "sizing" because of their perfect solubility in water so that the fibers can be thoroughly 65 impregnated therewith. Moreover they may

be totally removed by merely washing with water. They are prepared by combining the oil obtained by the sulfonation of the mixture of oxy-acid and oil not sulfonated with so much alkali that the oil shows a 70 neutral reaction when tested with litmus paper.

Basic oils are added to the dyes used for dyeing wool and half-wool, especially to acid dyes, in order to equalize the coloration and to protect the fibers. They are further used in dyeing cotton and half-silk with basic 75 colors, sulfur colors and the like. And in the operation of dressing fabrics with dextrin they are employed as a softening 80 agent. They are prepared by combining with the oil obtained by the sulfonation of the mixture of oxy acid and oil not sulfonated, so much alkali that upon test with an alcoholic solution of phenolphthalein a 85 slightly red coloration is produced.

Soaps are used as a brightening agent in dyeing and printing with Turkey red colors and other alizarin colors especially where the water at disposal is a hard water, because 90 no separation of lime-soap takes place when the improved soaps are dissolved in hard water. They are further made use of in the operation of fulling wool as also for scouring raw silk.

In order to obtain a soap, for instance, 95 500 kg. of oxy acid are mixed with 500 kg. of olive oil or another oil, the mixture is sulfonated and allowed to stand until a sample shows it to be perfectly soluble in distilled water to which some alkali has been added. Then the product is washed with water, and allowed to stratify when the under lye is carefully drawn off and the sulfonation product placed in a vessel provided with a stirrer and intimately mixed 100 therein with 700 liters of a soda lye of 20° Bé. If upon test with an alcoholic solution of phenolphthalein a slightly red coloration appears, then the soap will be ready, 105 otherwise the addition of soda lye must be continued until the said reaction is obtained.

Having fully described my invention, what I desire to claim, and secure by Letters Patent of the United States, is:—

1. The process of making fatty compounds for use as Turkey-red oils, which consists in sulfonating a fatty substance, treating the product with water to obtain an oxy-acid compound, mixing said oxy-acid compound with un-sulfonated oil, sulfonating the mixture, allowing it to stand until the proper degree of solubility has been attained, washing, allowing the oily product to stand in order to stratify, drawing off the product and mixing with alkali. 120

2. The process of making fatty compounds for use as Turkey-red oils, which consists in sulfonating a fatty substance, treating the product with water to obtain 125

an oxy-acid compound, mixing said oxy-acid compound with un-sulfonated oil, resulfonating the mixture, washing, drawing off the product and mixing with alkali.

5 3. The process of making fatty compounds for use as Turkey-red oils, which consists in sulfonating castor-oil, treating the product with water to obtain an oxy-acid compound, mixing said oxy-acid compound with un-sulfonated oil, sulfonating the mixture, allowing it to stand until the proper degree of solubility has been attained, washing, allowing the oily product to stand in order to stratify, drawing off the 10 product and mixing with alkali.

15

4. The process of making fatty compounds for use as Turkey-red oils, which consists in sulfonating castor-oil, treating the product with water to obtain an oxy-acid compound, mixing said oxy-acid compound with un-sulfonated oil, resulfonating the mixture, washing, drawing off the product and mixing with an alkali.

In testimony whereof I have hereunto set my hand in presence of two subscribing witnesses. 20 25

ALEXANDER SCHMITZ.
